UNITED STATES PATENT OFFICE.

FREDERICK CLARE, OF PRESTON, CANADA.

DESIGN FOR A RADIATOR.

SPECIFICATION forming part of Design No. 25,739, dated June 30, 1896.

Application filed May 11, 1896. Serial No. 591,172. Term of patent 7 years.

To all whom it may concern:

Be it known that I, FREDERICK CLARE, a subject of the Queen of Great Britain, and a resident of the village of Preston, in the county of Waterloo, in the Province of Ontario, Canada, have invented and produced a new and original Design for Steam or Hot-Water Radiators, of which the following is a specification, reference being had to the accompanying drawings, forming part thereof.

Figure 1 is a perspective view of a radiator. Fig. 2 is a cross-section, these two views being deemed necessary to fully illustrate my design.

The leading feature of my design consists in the top and bottom plates A of serpentine form and the double corrugated walls B.

A A are the top and bottom plates of the radiator, which are flat and in serpentine form from end to end.

B is a corrugated double wall between the top and bottom plates. The double walls B follow the serpentine contour of the top and bottom plates.

What I claim is—

The design for a hot-water or steam radiator herein shown and described.

FREDERICK CLARE.
